Attorney.

UNITED STATES PATENT OFFICE.

OTTO G. BECHER, OF OMAHA, NEBRASKA.

STENCIL FOR SAND-BLAST ETCHING.

1,265,989.

Specification of Letters Patent. Patented May 14, 1918.

Application filed August 18, 1916. Serial No. 115,734.

To all whom it may concern:

Be it known that I, OTTO G. BECHER, a citizen of the United States, and a resident of Omaha, in the county of Douglas 5 and State of Nebraska, have invented certain new and useful Improvements in Stencils for Sand-Blast Etching, of which the following is a specification.

My invention relates to the art of etching 10 glass, metals, porcelain, vitrolite, marble, and the like, by the use of a sand-blast operating through the openings of a stencil which determines the form, pattern or design to be etched. It is the object of 15 my invention to provide efficient and inexpensive stencils for use in such etching processes, and particularly to provide an inexpensive composition of matter such that a relatively thin layer thereof will resist 20 the action of a sand-blast sufficiently to enable a proper abrasion or etching of the surface not protected by the composition forming the stencil.

In the accompanying drawings Figure 1 25 is a perspective view illustrating a partially completed stencil embodying my invention, and Fig. 2 is a detail sectional view of the same.

In carrying out my invention I provide 30 a composition of which the approximate proportions and mode of preparation are as follows:

Ten (10) pounds of dried white glue is 35 covered with water in a suitable receptacle such as wooden pail or vat, and the receptacle then covered and put in a cool place for about 48 hours or until the glue is thoroughly softened. Equal parts of the softened glue and of water are then placed 40 in a vessel of suitable capacity, say 10 to 15 quarts, and said vessel placed in a larger vessel which is partially filled with water. To the mixture of glue and water there is added 1 to 1½ ounces of boiled linseed 45 oil, and about ½ ounce of powdered carbonate of magnesia. The ingredients are then heated by bringing the water in the outer vessel to boiling temperature for 15 to 20 minutes, and while heated the ingredients 50 are stirred and thoroughly mixed to a uniform consistency. Enough glycerin is then added to make the composition while hot have the consistency of thin syrup. The amount of glycerin required will average 55 about ½ ounce but will vary according to the quality of the glue and the season (summer

or winter) in which the preparation is used, more of the glycerin being used in warm weather.

For use in making stencils, a coating of 60 the described mixture or composition is applied to one side of sheets of paper of suitable size, the operation being preferably about as follows: A good quality of drawing paper is chosen, having a rough side 65 and a smooth side for drawing. A board, of suitable size for receiving the sheets of paper to be coated, is provided with a smooth surfacing as by placing thereon a plate of glass or smooth sheet-metal such 70 as copper, the board preferably having at opposite sides two projecting strips adapted to engage the edges of the paper sheet to confine the same between them. As each sheet of the paper is coated, it is first moistened by sponging with a damp cloth or the like on the rough side, then laid with the smooth side against the surface of the board between the retaining side-strips, and the sheets then pressed out smooth and flat upon 75 the surface. The composition, while still heated is then spread quickly over the surface of the paper, as evenly as possible, so as to form a coating having a thickness of about $\frac{1}{2}$ of an inch. The coating may be 80 smoothed and made more even and uniform in thickness by passing over it a roller or a strip of glass which has been warmed by immersion in heated water. The coated sheets when removed from the board are 85 hung up in a cool room where the temperature will not exceed 50 degrees F., the sheets being arranged on round sticks or the like so as not to be sharply bent and so that the 90 coated sides thereof will not come into contact with any object until they are desired for use. It is advisable not to prepare at one time more of the sheets than can be used in about a week, as after such time the 95 coating is liable to become hard and use- 100 less.

In the use of the coated paper, prepared as above described, the surface of the article to be etched or engraved is first thoroughly cleaned, and the coated side of the 105 paper is then applied to the surface and the paper rubbed or rolled to bring the composition coating into perfect contact with the surface, care being taken that no air-bubbles or foreign particles are allowed to 110 remain between the coated paper and the surface to which it is applied. When in

proper condition the prepared paper will adhere quite firmly to any smooth surface as of glass, metal, marble, porcelain, or the like, such as it may be desired to etch or 5 engrave by the use of a sand-blast, but the paper and composition coating may be detached from the surface by first loosening one edge thereof and then peeling the same off from said edge.

- 10 After the coated paper has been applied to the surface as above described, the desired design is drawn or stenciled on the surface of the paper, and thereafter said surface is washed over with a thin solution 15 of glue to form a thin transparent coating which is permitted to dry thereon. The design is then carefully cut out with a sharp knife, and the portions of the paper covering the parts which it is desired to etch or 20 engrave are removed by loosening the edges thereof and stripping or peeling them off, any adherent particles of the coating composition being afterward removed by scraping or otherwise detaching the same from 25 the portions of the surface which are to be etched. The article is then placed under the sand-blast and the sand blown against the exposed portions of the surface until the same is cut to the desired depth, after which 30 the stencil is removed and the portions of the surface to which it was attached cleaned off. In removing the stencil, if the same tends to adhere very firmly to the surface, it may be effectively loosened by packing it 35 for a time in wet sawdust.

In the accompanying drawings there is represented a plate 1 of glass having applied thereto a sheet 2 of paper prepared with a coating 3 of the described composition. It is assumed that the design to be etched on the glass consists of the letters forming the word Omaha, that the outlines of said letters have been drawn upon the surface of the paper after the attaching 40 thereof to the glass plate 1, and that the surface of the paper has been washed over with glue-water and dried to form a hard thin transparent coating (not indicated in the drawing). The final A of the word has been 45 cut out and removed, the H has been cut out and a portion thereof is being peeled off the glass, and the other letter A is being cut out with a knife 4. It will be understood that the thickness of the parts, especially of 50 the paper 2, is somewhat exaggerated, and that the entire drawing is intended merely to illustrate a typical use of the invention.

It will be understood that the composition provided by my invention is strongly adhesive and forms a tough, resilient and rubber-like layer or coating which offers great resistance to the action of a sand-blast, so

that said coating will remain adherent to and will protect the surface of the glass or other surface being etched, after the paper 65 body or backing 2 has been cut away by the sand-blast. In fact the part of the stencil which is actually effective, in protecting the surface of the article etched, is almost solely the layer or coating formed by the composition, while the paper forms a mere 70 backing or foundation which facilitates the application of the composition and the formation thereof into the desired design. The cutting out of the design is facilitated by 75 the washing over of the paper with glue-water, as described, this when dried causing the paper to be hard, stiff and relatively brittle, so that the knife may be easily pushed through it into the subjacent soft 80 and yielding layer of the coating or composition. The paper, by adhering more firmly to the composition than the latter does to the smooth surface of the glass or the like, facilitates the removal of the cut out parts 85 of the design, enabling the desired portions to be readily stripped or peeled off the surface of the article to be etched.

Now, having described my invention, what I claim and desire to secure by Letters Patent is:

1. A stencil-forming member for sandblast etching, comprising a sheet of paper, a relatively thick tough pliable adhesive coating on one side of said sheet adapted 95 to adhere to a smooth surface as of glass less firmly than to the paper, the opposite side of said sheet having a design outlined thereon, and a thin coating of a transparent hard material overlying said design and 100 hardening the paper sheet to facilitate cutting of the sheet along the outlines of the design to form a stencil after the adhesive coating is applied to the object to be etched.

2. A stencil-forming member for sandblast etching, comprising a backing-sheet of material such as paper, having a design outlined upon one side thereof, a dried transparent coating of sizing material overlying said design and stiffening the paper to facilitate cutting thereof upon the outlines of the design, and a relatively thick coating of a tough pliable sand-blast-resistant material strongly adherent to the other side of said backing-sheet, said sand-blast-resistant 110 coating adapted to adhere to a smooth surface as of glass less firmly than to the backing-sheet, whereby severed portions of the stencil-forming member may be readily 115 stripped from such a surface to expose portions thereof through the remaining parts of said member.

OTTO G. BECHER.
